C. A. PETERS

COMPOSITION STUDDING

Filed April 5, 1924

Charles Albert Peters Inventor

By
R. S. Barry

Attorney

UNITED STATES PATENT OFFICE.

CHARLES ALBERT PETERS, OF DOWNEY, CALIFORNIA, ASSIGNOR TO PETERS HOLDING COMPANY, A CORPORATION OF CALIFORNIA.

COMPOSITION STUDDING.

Application filed April 5, 1924. Serial No. 704,383.

My invention relates to studding and particularly to composition studding, and the general object thereof is to provide a reinforced studding formed of plastic material, 5 such as gypsum or plaster of Paris, mixed with sawdust or other suitable fibrous material as a binder, which will be capable of supporting a heavy load and withstanding great strains and which is fireproof.

10 A more particular object is to provide a studding of the character above stated which is confined between paper facing sheets on opposite sides thereof and which includes longitudinal and transverse reinforcing rods.

15 Another object is to provide a composition studding with means whereby the ends thereof may be securely attached at their lower ends to a floor structure and at their upper ends to an overhead structure and whereby the studding may be secured to either concrete or frame structures, as by embedding or anchoring in concrete or nailing to wooden structures.

20 With the foregoing objects in view, together with such other objects and advantages as may subsequently appear, my invention resides in the parts, and in the construction, combination and arrangement of parts as hereinafter described and claimed, and illustrated by way of example in the accompanying drawings, in which—

25 Figure 1 is a perspective view of my studding.

30 Figure 2 is a fragmentary longitudinal section of the upper end of my studding taken on line 2—2 of Figure 1.

35 Figure 3 is a horizontal section of my studding taken on line 3—3 of Figure 1.

40 Figure 4 is a fragmentary sectional perspective view of the lower end of my studding.

45 Figure 5 is a perspective view of one end of the anchoring plates for securing the lower and upper ends of the studding in a building structure.

50 Figure 6 is a fragmentary side view of the lower end of my studding, showing said end secured, by the plate shown in Figure 5, to the lower sill of a frame building.

55 Figure 7 is a view in side elevation show-

ing the manner of securing the lower end of the studding to a concrete floor structure.

Figure 8 is a fragmentary perspective view of the reinforcement.

60 My studding comprises a body 1 of plastic material such as a gypsum or plaster of Paris, mixed with sawdust or other suitable fibrous material as a binder, longitudinal reinforcing rods 2, transverse reinforcing rods 3, paper facing reinforcement sheets 4—4 secured on the opposite sides of said body, and anchoring plates 5 for attaching the lower and upper ends of the studding in a building.

65 The lower and upper ends 6 of the longitudinal reinforcing rods 2 project through and beyond the lower and upper ends of the plastic body 1. The ends 7 of the transverse reinforcing rods 3 extend through and beyond the outer and inner edges or surfaces 70 8 of the plastic body 1 on which sides there are no facing sheets 4 and provide means for securing lath or wall board to the studding. The reinforcing rods 2 and 3 may be of any suitable form but preferably are made of 75 wire of serpentine formation and are positioned so that the concave sides of the longitudinal rods 2 fit within concave sides of the transverse rods 3, thus interlocking said rods together in the plastic body 1.

80 Each of the plates 5 is formed with a rectangular embossment 9 on one side which forms a corresponding recess 10 on its opposite side. Each plate 5 is provided with nail holes 11 in its four corners and with 85 two holes 12 in its embossment.

85 Each end of the studding is placed against the embossment 9 of a plate 5, and the ends 6 of the longitudinal reinforcing rods 2 are inserted through the holes 12 and bent over into the recesses 10 on the under side of said plates. The plates 5 on the lower ends of the studding are nailed or otherwise secured to the sills or floor 14 of the building, with their recesses 10 facing said sills or floor 90 by means of nails or similar fastening elements 15, extending through the nail holes 11 in said plates and engaging said sills or floor, thus firmly securing the lower end of the studding to said sills or floor.

95 100 Where the studding is employed in a frame structure, the plates 5 are secured by

nailing to a timber 16 as shown in Figure 6, and where the studding is employed in a class "A" or fireproof building construction in which the floors and beams are formed of 5 reinforced concrete, the end plates may be embedded in the concrete 17 as shown in Figure 7, thereby firmly anchoring the ends of the studding in the structure.

The upper end plates 5 are secured to 10 plates or beams in a similar manner, whereby the studding 11 will be securely and rigidly held in place. The studding is set in place with the end portions 7 of the transverse reinforcements projecting from the 15 inner and outer edges of the studding, constituting the sides thereof on which the wall facing is to be formed, whereupon any suitable sheet lathing or composition board 18 may be secured and tied to the studding by 20 engaging the lath or board with the end portions of the transverse rods 3 by bending the latter thereon, as illustrated in Figure 3 which shows a wall board as applied to the studding. Where the ordinary metal lath 25 is used, the uncovered or exposed areas of the plastic forming the edges of the studding provide surfaces to which plaster will adhere. The manner of forming the studding proper is set forth in my copending 30 application, filed April 5, 1924, Ser. No. 704,382.

I claim—

1. A composition studding comprising a body of plastic material, longitudinal reinforcing rods extending through said body, facing sheets covering opposite sides of said body, transverse reinforcing rods extending through said body between said facing sheets and projecting from opposite sides 40 thereof, said longitudinal and transverse reinforcing rods being embedded in said body, and means for securing the lower and upper ends of said body to a building structure.

2. A composition studding comprising a body of plastic material, paper reinforcing facing sheets secured to opposite sides of said body, and a series of rods carried by said body of plastic material having bendable end portions projecting from at least 50 one side thereof, and means for securing the ends of the studding in a building structure; said rods being embedded in said body.

3. A composition studding comprising a body of plastic material, reinforcing facing sheets on opposite sides of said body, longitudinal reinforcing rods extending through said body and projecting beyond the ends thereof, transverse reinforcing rods extending through said body and projecting from 60 the sides thereof, and means for securing the ends of the studding in a building structure.

4. A composition studding comprising a body of plastic material, serpentine reinforcing rods extending through said body and having their terminations projecting there-

from, serpentine rods extending transversely through said body having their terminations projecting therefrom, and means for securing the ends of the studding to a building structure.

5. A composition studding comprising a body of plastic material, serpentine longitudinal reinforcing rods extending through said body, serpentine reinforcing rods extending transversely through said body with 75 their concave sides interlocked with the concave sides of the longitudinal serpentine rods, and means for securing the ends of the studding to a building structure.

6. A composition studding comprising a body of plastic material, a reinforcement including longitudinal rods extending through the body and out the ends thereof, plates formed with recesses and provided with holes communicating with said recesses, 85 means for securing said plates to a building structure with said recesses facing outermost and with the ends of the studding resting against said plates, and the ends of said reinforcing rods extending through said holes 90 and bent over in said recesses.

7. A composition studding comprising a body of plastic material, a reinforcement including transverse rods extending through said body and out through an edge thereof, 95 means for holding said transverse rods against longitudinal movement in said body, means for securing the ends of the studding to a building structure, sheet wall forming material placed against the edge through 100 which said rods project, the ends of said rods being bent to engage and tie said sheet material to the studding.

8. A studding comprising an elongated body portion of rectangular cross section 105 formed of a plastic composition, paper reinforcing sheets facing opposite sides of said body, a series of reinforcing rods extending transversely through said body between said facing sheets and having their end portions projecting beyond the faces of the body, said projecting end portions being adapted to be bent, and reinforcing rods extending longitudinally through said body with 110 which said transverse reinforcing rods are 115 engaged whereby the latter are held against longitudinal movement.

9. A studding comprising an elongated body portion of rectangular cross section, facing sheets adhered to said body on opposite sides thereof, serpentine reinforcing rods extending longitudinally through said body, and a series of spaced serpentine rods extending transversely through said body in the direction of the facing sheets, the concave 120 portions of which interlock with concave portions of the longitudinally extending rods, and the end portions of which transverse rods project beyond opposite faces of the body portion and are adapted to be bent 125 130

to engage sheet material to be carried on the studding.

10. A composition studding comprising a body of plastic material, fibrous reinforcing sheets adhered to opposite sides of said body, reinforcing rods extending longitudinally through said body and embedded therein, the

end portions of said rods projecting beyond the ends of said body, and a series of transverse rods embedded in said body having end portions projecting from at least one edge thereof. ¹⁰

CHARLES ALBERT PETERS.
